UNITED STATES PATENT OFFICE.

JOHN STONE STONE, OF CAMBRIDGE, MASSACHUSETTS, ASSIGNOR TO STONE TELEGRAPH AND TELEPHONE COMPANY, OF BOSTON, MASSACHUSETTS, A CORPORATION OF MAINE.

SPACE TELEGRAPHY.

No. 916,895.

Specification of Letters Patent.

Patented March 30, 1909.

Application filed December 14, 1905. Serial No. 291,702.

To all whom it may concern:

Be it known that I, JOHN STONE STONE, a citizen of the United States, and resident of Cambridge, in the county of Middlesex and 5 State of Massachusetts, have invented a new and useful Improvement in Space Telegraphy, of which the following is a specification.

My invention relates to the art of transmitting intelligence from one station to another by means of electromagnetic waves without the use of wires to guide the waves to their destination; and it relates more particularly to systems for receiving signals 15 transmitted by such waves.

In the art of wireless telegraphy no problem is of greater importance from an industrial and commercial standpoint than that of rendering the receiving instruments of 20 wireless telegraph stations immune from interference. There are two principal kinds of interference: First, that which arises from such stray electromagnetic waves as are produced by lightning, by magnetic storms, 25 by sparks in neighboring circuits, such for instance as occur in trolley circuits, and also from electromagnetic waves emanating from wireless telegraph stations other than that with which communication is desired; and 30 second, that which arises from electrical charges which accumulate upon the vertical oscillator or elevated receiving conductor under various conditions of weather, provided said elevated conductor has no adequate 35 electrical connection to the earth.

In my prior Letters Patent Nos. 767,994, 714,756 and other Letters Patent, I have disclosed means for rendering the receiving instruments immune from interference of the 40 first class above mentioned, namely, interference which arises from electromagnetic waves emanating from foreign stations, and which arises from abrupt or impulsive electrical forces; and the object of my present 45 invention is to provide a wireless telegraph receiving system, the instruments of which shall be immune from interference of the second class, namely, "static" interference.

The greatest security from static interference is obtained by providing the elevated receiving conductor with an adequate conductive connection to earth and by placing the receiving device in a local circuit made resonant by a coil and a condenser to the fre-

quency of the electrical oscillations to which 55 the receiver is intended to respond, as shown in my above mentioned Letters Patent. However, in some instances it is advisable to include a condenser or condensers in the elevated conductor as more fully explained in 60 connection with some of the figures of my Letters Patent No. 767,994, and in connection with my Letters Patent Nos. 767,990, 802,425 and other Letters Patent.

By the means set forth in the present application static interference is readily overcome even when a condenser is serially included in the elevated conductor, for by said means said conductor may always be given a metallic connection to the earth sufficient 65 to maintain it clear of static charges without in any appreciable degree interfering with its operation as a receiving conductor; and it is readily overcome even if the oscillation detector is included directly in said 70 receiving conductor.

I accomplish the hereinbefore stated objects of my invention by connecting across the terminals of a condenser serially included in the elevated conductor, or across 75 the terminals of an oscillation responder similarly included in said conductor, or across the terminals of that portion of the conductor which includes said condenser and responder, a device having, for the frequency of the waves to be received, an impedance greater than the impedance of said condenser, said responder, or both.

My invention may best be understood by having reference to the drawings which accompany and form a part of this specification and which illustrate diagrammatically several forms of apparatus and circuit arrangements whereby the hereinbefore stated objects may be carried into effect.

In the drawings, Figure 1 represents a space telegraph receiving system in which the oscillation responder is serially included in the elevated conductor; Fig. 2 represents a space telegraph receiving system in which the oscillation responder and a condenser are serially included in the elevated conductor; Fig. 3 represents another type of space telegraph system; and Figs. 4, 5 and 6 represent space telegraph systems embodying elevated conductor systems of the type set forth in my Letters Patent No. 802,425.

In the figures, A is a source of varying

current such for example as an alternating current generator.

M M' M'' M''' are transformers.

I₁ I'₁ and I''₁ are transformer primaries, and I₂ I'₂ I''₂ are transformer secondaries which preferably are so related to their respective primaries as to produce transformers of large magnetic leakage.

10 C C₁ C'₁ C'' C'' C₂ C₃ C₄ C₅ and C₆ are condensers.

P P' are oscillation detectors of any suitable type.

B B' are batteries.

L is a protective inductance.

15 L₁ L₂ are tuning inductances.

V is an elevated conductor consisting of a plurality of wires, of which the wires v v are employed for receiving.

K is a key.

20 R is a resistance which with the battery B constitutes a potentiometer.

T T' are signal-indicating devices.

In Fig. 1 I have shown a simple wireless telegraph receiving system of the kind first 25 employed in this art in which the oscillation detector P''' is included in the elevated conductor. Connected across the terminals of the electrical device or detector P''' is a protective coil L having for waves which have 30 the high frequency of the waves to be received, an impedance much greater than the impedance of the device P''', so that the coil will serve as a by-path for the currents due to the passage of the static charges in the 35 elevated conductor V to earth. Such an inductance coil, which, as before stated, has an impedance for the high-frequency oscillations created in the elevated conductor by the waves to be received, which is very high 40 compared to the impedance of the device P''', operates practically as an open circuit for such oscillations, while affording a ready path to earth for the electrical charges which, in its absence, would accumulate 45 upon the elevated conductor and produce disruptive discharges to earth, thereby operating the oscillation detector.

In Fig. 2 is shown practically the same simple system as in Fig. 1 with the addition 50 of a condenser C₆ serially connected in the elevated conductor. The capacity of this condenser is so large as not to impede appreciably the passage of the high-frequency oscillations of wireless telegraphy while operating practically as an open circuit for the more slowly varying currents by which the elevated conductor is maintained free of static charges and which pass to earth by way of the protective inductance coil L, 55 which as before stated, operates practically as an open circuit for said high-frequency oscillations.

In Fig. 3 I have shown a receiving system, in which the circuit C₃ C₅ L₂ C₂ is made 60 resonant to the frequency of the waves to

be received, and in which the capacity of the condenser C₅ is small compared to the capacity of the condenser C₃. The protective coil L connected across the terminals of that portion of the elevated conductor which 70 includes the condensers C₃ and C₄ operates as a by-path around said condensers for the currents produced by the static charges, while impeding the passage to earth of the high-frequency oscillations created by the 75 waves to be received. It will be noted that this coil L does not assist in tuning any circuit in any of the systems disclosed in the present application.

In Fig. 4 I have shown the receiving system set forth in my Letters Patent No. 802,425, in which the condenser C₁ insulates a portion of the elevated conductor from the earth and is shunted by the protective coil L which as in the figures already discussed 85 affords a bypass to earth by way of the primary I'₁ for the currents resulting from the static charges in the elevated conductor. Were the coil not employed, said charges would accumulate until a sufficient potential 90 difference existed between the terminals of the condenser to produce disruptive discharges to earth which would have the effect of creating false signals in the detector P'.

It is, as set forth in my Letters Patent No. 95 167,979, advantageous to employ an elevated conductor consisting of a plurality of wires, and I have discovered that under certain circumstances it is preferable to employ a smaller number of wires for receiving than 100 for transmitting. In Fig. 5 I have shown a receiving system, having the serially included condenser C₁ shunted by the protective inductance coil L, and the transmitting system set forth in my Letters Patent No. 105 714,756 associated with a multiple wire transmitting elevated conductor. The switch 5 pivoted between the jaws 4 and connecting, in the position shown, said jaws with the jaws 4', connects the transformer secondary 110 I₂ with all the wires, v and v' of the multiple transmitting conductor V. When the switch 5 is thrown over so as to connect the jaws 4 with the jaw 3', the receiving system is connected with a portion only of the wires of 115 the multiple elevated conductor. In the system shown in Fig. 5 the two outer wires v v are connected to the receiving system when the switch is thrown over so as to connect the jaws 4, and 3', but obviously any given 120 number of said wires might be so connected to the receiving system by said switch 5 when in such position.

In Fig. 6 I have shown the same system as Fig. 5 provided with means operated by 125 the sending device K for automatically connecting a given number of the wires of the multiple elevated conductor V with the receiving system and for connecting all said wires with the transmitting system. In this 130

figure the key carries at one end one member W of the electrolytic receiver P, and in the normal position of said key the member W is in contact with its coöperating member, 5 the wires v' v' of the elevated conductor are disconnected from the rest of the system, and the wires v v are connected to the receiving system which is earthed at the point E. Upon the depression of the key, the stud 6 10 presses the spring 7 down upon the contact o', thereby closing the contact k''' and short-circuiting the receiving system at the point k''' between the terminals o, o' of the receiving system and connecting the secondary 15 I₂ to earth E by way of said spring 7. At the same time, or shortly before or shortly afterward, the member W is separated from the member P, thereby rendering the receiver inoperative, and either before or 20 after, or between said operations, and at any time prior to the closure of the contact k', the circuit of the magnet I is closed by the closure of the contact k''. The energization 25 of the magnet I by the battery B' effects the closure of the contact k by the attraction of the armature 2 which is connected with the conductors v' v' and thereby, before the closure of the contact k', automatically connects all the wires of the elevated conductor 30 V with the transmitting system.

I claim,

1. In a wireless telegraph receiving system, an elevated conductor system including a condenser, and protective means connected 35 across the terminals of said condenser and having, for the frequency of the waves to be

received, an impedance so much greater than the impedance of said condenser that it operates practically as an open circuit for oscillations of said frequency.

2. In a wireless telegraph receiving system, an elevated conductor system including a condenser, and a protective inductance connected across the terminals of said condenser and having, for the frequency of the 40 waves to be received, an impedance so much greater than the impedance of said condenser that it operates practically as an open circuit for oscillations of said frequency.

3. In a wireless telegraph system, a transmitting system, a receiving system, an elevated conductor comprising a plurality of wires, and means for connecting a small number of said wires with the receiving system and for connecting all said wires with 45 the transmitting system.

4. In a wireless telegraph system, a transmitting system, a receiving system, a sending device, an elevated conductor comprising a plurality of wires, and means operated by 50 said sending device for automatically connecting a small number of said wires with the receiving system and for connecting all said wires with the transmitting system.

In testimony whereof, I have hereunto 55 subscribed my name this 8th day of Dec. 1905.

JOHN STONE STONE.
